(57) **CLAIM**

The ornamental design for a bottle carrier, as shown and described.

DESCRIPTION

FIG. 1 is a front perspective view of a bottle carrier according to the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom perspective rear view thereof; and,

FIG. 9 is a front perspective view of the bottle carrier showing a bottle contained therein in broken lines.

(Continued)

The broken lines showing a bottle are included for the purpose of illustrating environment of the design and form no part of the claimed design.

1 Claim, 4 Drawing Sheets
